UNITED STATES PATENT OFFICE

HARRY G. MILLER, OF DENVER, COLORADO, ASSIGNOR TO MILLER SERVICE TOOL CO.,
OF MILWAUKEE, WISCONSIN, A CORPORATION OF WISCONSIN

GRINDING MACHINE

Application filed January 26, 1926, Serial No. 83,827. Renewed June 13, 1930.

This invention relates to improvements in grinding machines.

It is the object of this invention to produce a simple and inexpensive machine for grinding valve tappets, shims and similar articles in a convenient manner and with great accuracy.

The invention, briefly described, consists of a base to the upper surface of which a 10 motor is secured. A bracket is also secured to the base and carries a grinding disk that is connected with the motor by means of belts in such a manner that it will be rotated by the motor. An arm or support is mounted for 15 oscillation about an axis that lies below the axis of the grinding disk and in the plane of rotation of the disk. Secured to the upper end of the oscillatory arm is a turret head that can be rotated about an axis which is 20 perpendicular to the axis of the arm; this turret head has a hollow cylindrical sleeve to which the tappet, which is to be ground, is secured and to which the chuck for holding the shims may also be secured. Means have 25 also been provided for adjusting the oscillatory arm towards and away from the grinding disk and for limiting the extent of the oscillation.

Having thus briefly explained my invention, I shall now proceed to describe the same in detail, reference for this purpose being had to the accompanying drawings in which the invention has been illustrated and in which:

Fig. 1 is a top plan view of the machine;

Fig. 2 is an elevation looking in the direction of arrows 2—2, Fig. 1, portions being shown in section or broken away so as to better disclose the construction;

Fig. 3 is a section taken on line 3—3, Fig. 1;

Fig. 4 is a section taken on line 4—4, Fig. 1;

Fig. 5 is a longitudinal section of the rotatable sleeve;

Fig. 6 is a fragmentary section taken on line 4—4, Fig. 1, showing a magnetic chunk substituted for the tappet; and,

Fig. 7 is a view of the face of the chuck, 50 two shims having been indicated by dotted

lines as being in position on the face of the same.

In the drawings numeral 5 designates the base upon which is mounted and secured an electric motor 6. Also, mounted upon the base is a frame member or bracket 7 which extends upwardly above the motor and in which is journaled the shaft 8 upon which is mounted, so as to rotate therewith, a grinding wheel 9 of emery, carborundum or any other suitable abradant. Secured to the motor shaft 10 so as to rotate therewith is a pulley 11 which is relatively large and connected by a belt 12 with the pulley 13 on the grinding wheel shaft 8. When the motor operates the grinding wheel will be rotated at a high speed. Extending upwardly from the base member directly in front of the grinding wheel so as to be bisected by a plane passing through the middle of this wheel are two lugs 14 and 15, the former of which has a cylindrical socket 16 whose central axis is parallel with the plane of rotation of the wheel 9 and which preferably lies in the plane of the center of the wheel. The lug 15 has a threaded opening 17 whose axis is in line with the axis of the opening 16. A threaded tubular member 18 has a hand wheel 19 secured to one end and cooperates with the threads on the walls of the opening 17 so that when it is rotated it will move towards or away from the lug 14, as the case might be.

A pivot or shaft 20 has one end provided with a cylindrical part 21 that fits into the opening in member 18 and extends entirely through this member in the manner shown in Fig. 4. The other end of shaft 20, which has been designated by numeral 22, is somewhat larger in diameter than the part 21 and has an axial opening 23. The tubular end 22 extends into the opening 16. A spring 25 has one end abutting the bottom of the opening 23 and the other the bottom of the opening 16. This spring is under compression and produces a force which tends to hold the shoulder 26 in contact with the inner end of the screw 18. It is now evident that by rotating the screw 18, the shaft 20 may be moved in the direction of its axis. The screw 18 moves the shaft 20 positively in one direction

and the spring 25 returns it. Directly underneath the shaft 20, the base 5 has an opening 27 whose function will hereinafter appear. An arm 28 has a hub portion 29 that is provided with an opening of the proper diameter to receive the tubular part 22 and is clamped in position on the latter by means of the set screws 30. The length of the hub 29 is less than the distance between the adjacent surfaces of the lugs 14 and 15 and may therefore be moved in one direction or the other until its ends come into contact with the adjacent surface of one of the lugs 14 or 15. An arm 31 extends downwardly from the under side of a hub and terminates within the opening 27. A screw 32 extends through a threaded opening in this arm and serves as an adjustable stop which limits the extent of oscillation of the arm 28. The upper end 20 of the arm 28 is provided with a flat part 33 whose upper surface is plane. A stud 34 projects upwardly from the part 33 and extends perpendicularly with the upper surface thereof. A part that may be termed a turret head has a base 35, the lower side of which has a plane surface 36 that is adapted to rest upon the plane upper surface of the part 33. The part designated by numeral 35 has an upwardly extending arm 37 whose upper end is provided with an opening 38 for the reception of a bushing 39. The arm 37 is integral with a U-shaped wall 40 which terminates in an upwardly extending portion 41 having a bearing that corresponds to the upper end bearing 42 of the arm 37 and has an opening 43 for the reception of a bushing 44 which corresponds to the bushing 39. A tubular journal or chuck 45 is rotatably mounted in the bushings 39 and 44. The chuck 45 is also provided with a longitudinal slot 46 within which is located a bowed spring 47 whose curvature is such that it extends into the interior of the chuck 45 in the manner shown in Fig. 5. A pulley 48 is secured to the tubular member 45 by means of a set screw 49 in the manner shown in Fig. 4. The length of the hub pulley 48 is the same as the distance between the adjacent surfaces of the parts 41 and 42 so that it holds the tubular journal 45 against longitudinal movement. In Fig. 4 I have shown a valve tappet in place in the tubular rotatable member 45. When the tappet is in place the spring 47 will exert pressure against its outer surface and thereby produce sufficient friction to prevent it from rotating relative to the member 45. As this machine is intended for grinding tappets for all makes of cars and as these are made in several different sizes, it is necessary to provide as many different chuck members like that shown in Fig. 5 as may be necessary to take care of the different sizes of tappets. The difference between the several tubular chuck members 45 is merely in the internal

diameter, which must be suitable for the tappet to be ground. The arm 28 has an opening 51 that forms a bearing for a shaft 52 to opposite ends of which pulleys 53 and 54 (Fig. 2) are connected. A belt 55 connects the pulley 53 with the pulley 56 on the drive shaft 10, while a similar belt 57 serves to transmit motion from the pulley 54 to the pulley 48. A handle 58 is secured to the bottom portion of the bearing member 41, in the manner shown in Fig. 3, and is used for rotating the part 35 on the part 33 and for rocking the parts about the axis of the shaft 20. It will be observed that the turn table pivot stud 34 is located substantially at the intersection of the central plane of the pulley 54 with the central plane of the pulley 48 which drives the work holding chuck 45, whereby adjustment may be made without unshipping the belt.

When a tappet face, like that indicated by numeral 59, is to be ground the tappet stem 50 is inserted into the opening in member 45 so as to assume the position shown in Fig. 4. By means of the hand wheel 19, the parts can be moved towards or away from the periphery of the grinding disk 9.

If the disk is to be ground perfectly flat the parts are so adjusted, by rotation about the pivot 34, that the axis of the tappet 50 lies parallel to in the same plane with the axis of the shaft 20. If, however, the surface 59 is to be made slightly convex, as is often desirable, the axis of the tappet is placed at an angle with the axis of the shaft 20 about which it rocks. When so placed the face of the tappet would be ground to a conical shape were it not for the rocking movement of the support whereby the tappet is oscillated across the central plane of the grinding wheel whereby the contact point at the end of the stroke is brought a little closer to the margin of the tappet head than it is at the center of the stroke when in a horizontal plane through the axis of the grinding wheel. The part 35 is held in adjusted position with respect to the part 33 by means of a clamp 60. After the parts 35 and 33 have been properly adjusted, the parts are adjusted with respect to the grinding disk by means of the screw 18. By rocking the parts about the shaft 20, while the tappet is being rotated in contact with the grinding wheel, the tappet face 59 is ground to the desired convex shape.

I want to call attention at this point to the fact that in the grinding operations for which this machine is to be used, the axis of the tappet when at its maximum height above the axis of oscillation must be at the same vertical height as the axis of the shaft 8, all as shown in Fig. 4. The fact that the surface to be ground is rotated during the grinding operation makes it perfectly true and even.

It is also possible to employ this machine for the grinding of flat objects such as shims, washers and the like. In order to be able to hold these objects, while they are rotated in contact with the grinding surface of the rotating disk 9, a magnetic chuck has been provided. This chuck has been shown in Figs. 6 and 7 as consisting of a round steel disk 61 that is rigidly and nonrotatably connected with the cylindrical stem or shank 62 which is adapted to be inserted into the interior of the rotatable tubular sleeve or chuck 45. The stem 62 has a longitudinal slot or groove 63 with which the spring 47 engages so as to lock the stem 62 and attached disk 61 against rotation relative to the chuck 45. The disk 61 is made of hardened steel of large magnetic retentivity and magnetized so as to have a north pole N on one side and a south pole S on the other. A groove 64 extends diametrically across the disk intermediate the poles so as to coincide with the neutral axis of the disk when considered as a magnet. It is evident that the electromagnet just described, will hold light objects of iron or steel, such as shims, 65 which have been indicated by dotted lines in Figs. 6 and 7. The disk 61 has been provided with a plurality of holes 66 for the reception of pins 67. These pins engage the shims or other objects that are to be ground, somewhat in the manner shown in Fig. 7, and prevents them from sliding along the surface of the chuck while being ground. Thin flat objects may by this means be ground with great exactness to any thickness desired. Although I have shown shims as being the objects to be secured to the magnetic chuck, it is, of course, evident that any flat object of any shape may be ground and it is also possible to secure piston rings to the chuck so as to grind them to any thickness desired.

Having now described the invention what I claim as new is:

1. A machine for grinding valve tappets and the like, comprising, in combination, a rotatable grinding disk, an oscillatory arm mounted for oscillation in continuous reciprocation during grinding operations about an axis that lies in the plane of rotation of the grinding disk and below the axis of rotation thereof, means for limiting the range and adjustably determining the field of reciprocation, a turret head carried by said arm, said head being mounted so as to be rotatable about an axis that is parallel with the axis of the arm, a tubular work holding chuck member mounted for rotation in said turret and common means for driving said tubular member and grinding disc including belting having a set of pulleys located adjacent to the axis of oscillation of said oscillatory arm and upon an axis transverse thereto.

2. In a valve grinding machine having a rotatable grinding wheel and a work supporting arm oscillatable continuously across the

plane of rotation of the wheel during grinding operations, a work holder mounted for adjustment about an axis normal to the axis of arm oscillation, and a chuck rotatably mounted on said holder having its axis of rotation extending substantially radially of a plane of rotation of the wheel.

3. In a valve grinding machine, a rotatable grinding wheel, an arm freely oscillatable continuously during grinding operations about an axis disposed substantially in a plane of rotation of the grinding wheel, a holder for a valve stem carried by the arm and movable about an axis disposed in a plane parallel to the plane of rotation of the wheel and normal to the axis of oscillation of the arm, a chuck for a valve carried by said holder and rotatable about an axis which may by movement of the holder be disposed substantially parallel to or slightly angularly relative to the plane of rotation of the wheel, said chuck axis being also disposed in an arc of oscillation about the axis of said arm substantially coinciding with a plane parallel to the axis of said arm and disposed in the axis of the wheel.

In testimony whereof I affix my signature.
HARRY G. MILLER.
